(57) **CLAIM**

The ornamental design for a tire as shown and described.

DESCRIPTION

FIG. 1 is a side perspective view of a first embodiment of a tire showing our new design, it being understood that the tread pattern is repeated throughout the circumference of the tire, the opposite side being the same as that shown; FIG. 2 is a front elevational view of the first embodiment of the tire;

FIG. 3 is a side elevational view of the left side of the first embodiment of the tire;

FIG. 4 is a side elevational view of the right side of the first embodiment of the tire;

FIG. 5 is an enlarged fragmentary view of FIG. 2 taken along line 5-5;

FIG. 6 is a first transversal section view of the first embodiment of the tire taken along line 6-6 of FIG. 7;

FIG. 7 is an enlarged fragmentary view of FIG. 2 taken along line 5-5;

FIG. 8 is a side perspective view of a second embodiment of a tire showing our new design, it being understood that the tread pattern is repeated throughout the circumference of the tire, the opposite side being the same as that shown; FIG. 9 is a front elevational view of the second embodiment of the tire;

FIG. 10 is a side elevational view of the left side of the second embodiment of the tire;

FIG. 11 is a side elevational view of the right side of the second embodiment of the tire;

FIG. 12 is an enlarged fragmentary view of FIG. 9 taken along line 12-12;

FIG. 13 is a transversal section view of the second embodiment of the tire taken along line 13-13 of FIG. 14; and,

FIG. 14 is an enlarged fragmentary view of FIG. 9 taken along line 12-12.
